UNITED STATES PATENT OFFICE.

FRANCIS H. BRENNAN, OF ALBANY, NEW YORK.

CENTERING DEVICE.

1,255,507.

Specification of Letters Patent.

Patented Feb. 5, 1918.

Application filed June 15, 1917. Serial No. 175,004.

To all whom it may concern:

Be it known that I, FRANCIS H. BRENNAN, a citizen of the United States, residing at Albany, in the county of Albany and State 5 of New York, have invented certain new and useful Improvements in Centering Devices, of which the following is a specification.

This invention relates to centering devices and has as its object to provide a centering 10 device which may be readily applied to a piece of work for the purpose of quickly and accurately determining the geometric center thereof and which device may also be employed in scribing a piece of work and in 15 marking the median or center line of a bar, plate, or other similar piece of work.

Another aim of the invention is to provide a centering device so constructed that it will 20 operate as accurately and as efficiently on the largest as well as the smallest sizes of work to which it is applicable.

In the accompanying drawings:

Figure 1 is a perspective view of the device illustrating the manner in which the 25 same may be applied to the end of a shaft or other cylindrical body in order to determine the geometric center thereof;

Fig. 2 is a plan view of the device illustrating the manner in which the same is to 30 be employed in determining and indicating the median or center line of a bar or plate;

Fig. 3 is a similar view illustrating the manner in which the device may be employed in determining the geometric center 35 of a polygonal body or piece of work;

Fig. 4 is a vertical longitudinal sectional view through the device applied to the end of a shaft;

Fig. 5 is a side elevation of the device 40 applied to the end of a shaft.

The device embodying the present invention comprises a frame supporting, centrally, a marking or scribing point and carrying work-engaging members between 45 which the said point is centrally located. The frame includes center bars 1 which are arranged in crossed relation, and two pairs of side bars each indicated by the numeral 2. The side bars of each pair at their inner ends 50 are mutually pivotally connected, as indicated by the numeral 3, and at a point midway between their ends the bars of each pair are pivotally connected, as at 4, with the corresponding ends of the center bars 1. 55 At their point of intersection the center bars

1 support a tubular post 5 which is reduced in diameter at its lower end, as at 6, and has its said end fitted through openings in the said center bars, a collar 7 being riveted upon the reduced end of the post below the 60 said center bars so as to hold the parts in proper assembled relation and yet permit of relative angular movement of the bars 1. Freely slidably fitted in the tubular post 5 is a combined centering and scribing pin 8 65 having a conical pointed end 9 designed to be driven into the work to indicate the center thereof or to mark a line upon work when it is desired to determine and indicate the median or center line thereof. The pin 8 is 70 flattened upon one side throughout a portion of its length, as indicated by the numeral 10, and a set screw 11 is threaded through the wall of the tubular post 5 and, by engagement with the shoulders at the 75 ends of the flattened portion 10 of the said pin, is designed to limit the sliding movement of the pin in the said post. However, the pin may be held at any desired position of adjustment, as, for example, in scribing 80 work or drawing the median line thereof, by tightening the said set screw 11 after the pin has been brought to the desired position of adjustment.

Depending from the outer end of each of 85 the frame bars 2 is a work-engaging member preferably in the nature of a cylindrical post 12 having its upper end reduced, as at 13, so as to permit of the device being applied to work having a bur, shoulder, or the 90 like, as clearly shown, for example, in Figs. 4 and 5 of the drawings. While in the present instance the work-engaging members are in the nature of posts which are cylindrical in form, it will be understood that various 95 other forms of said members may be employed. It will be observed by reference to the drawings that there are, in effect, two pairs of the work-engaging members or posts 12 and that in all positions of adjustment of the frame members the said pairs of work-engaging members will be equi-distantly spaced at the opposite sides of the centering or marking pin 8. It is preferable that the center bars 1 be of greater 100 length than the bars 2 so that the outer ends of the bars 2 will be given an increased throw when the frame is adjusted for the application of the device to a relatively 105 large piece of work. In other words, when 110

the frame is adjusted so as to adapt the device for application to a relatively small piece of work the two pairs of work-engaging posts 12 will be brought relatively close together so as to engage opposite sides of the piece of work and with the parts thus adjusted the posts of each pair will be located relatively close to each other. However, due to the increased length of the bars 1, when 10 the frame is opened or spread so as to adapt the device for application to a large piece of work, the posts 12 of each pair will be gradually moved away from each other a relatively great distance and this distance will 15 increase with the increased opening or spreading of the frame. Thus when the frame is adjusted for application to a large piece of work the posts of each pair will be separated a greater or less distance so as to 20 engage the work at more or less widely separated points, thereby steadyng the device and increasing the accuracy thereof.

It is preferable that one of the pivots 4 shall consist of a bolt 14 upon which is 25 threaded a thumb nut 15 so that by tightening the nut, the members comprising the frame of the device may be locked against relatively movement after the desired adjustment has been obtained.

Having thus described the invention, what 30 is claimed as new is:

1. In a device of the class described, crossed pivoted center bars, oppositely arranged sets of side bars, the bars of each set being pivotally connected at their inner 35 ends and between their ends being connected pivotally with the ends of the center bars, a marking element located at the pivot for the center bars, and a work-engaging element carried and supported solely by the 40 outer ends of each of the side bars.

2. In a device of the class described, crossed pivoted center bars, oppositely arranged sets of side bars, the bars of each set being pivotally connected at their inner ends 45 and between their ends being connected pivotally with the ends of the center bars, a marking element located at the pivot for the center bars, and work-engaging elements carried by the outer ends of the side bars, 50 the center bars being of greater length than the side bars whereby when the frame is adjusted for application to work of relatively large size, the work-engaging members at each side of the frame will be relatively 55 separated.

In testimony whereof I affix my signature.
FRANCIS H. BRENNAN. [L. S.]
